UNITED STATES PATENT OFFICE

WILLIAM D. LA RUE, OF PHILADELPHIA, PENNSYLVANIA, ASSIGNOR TO VICTOR TALK-
ING MACHINE COMPANY, A CORPORATION OF NEW JERSEY

DIAPHRAGM FOR ACOUSTICAL INSTRUMENTS

Application filed April 29, 1935, Serial No. 36,764, and in Great Britain May 1, 1934.

This invention relates to diaphragms for acoustical instruments, and more particularly to diaphragms of the pleated type.

It has heretofore been proposed to provide a pleated diaphragm by folding or reversely flexing a substantially rectangular strip of suitable material such, for example, as paper, the folds extending over the entire surface of the strip. The opposite ends of the strip are then suitably secured together; the cylinder thus formed is flexed into a cone, and the apex of said cone is pushed down, the outer ends of the pleats opening out and forming the periphery of a disk-like diaphragm. The flattened outer ends of the pleats are then secured in any desired manner to a rigid surrounding frame or annular member and the inner ends of said pleats are secured, as by means of glue, to a center bushing or cylindrical member. When so formed, the ridges resulting from the folding operation extend radially in all directions from said center bushing.

A diaphragm of this character may be formed of large diameter since the same will vibrate as a whole, and as its entire surface is normally under tension it possesses the advantage that it will not produce the disagreeable effect which is technically known as blasting or shattering. However, it has been found that difficulty is sometimes experienced in rendering the diaphragm wholly indifferent to atmospheric changes. Variations in temperature and humidity have a tendency to cause the diaphragm to expand or contract. If the material expands, for example, the pleats tend to pucker, particularly adjacent the rigid supporting ring, and the tension of the diaphragm is reduced. Such a condition results in a decrease in the volume and an impairment of the quality of sound produced by the diaphragm.

An object of the present invention is to provide a pleated diaphragm which is so formed that it will not be adversely affected

by atmospheric changes, that is, one which is so constructed that atmospheric changes which tend to affect the material of the diaphragm will not result in a decrease in the volume or an impairment of the quality of sound produced by said diaphragm.

Another object is to provide a pleated diaphragm which is so formed that the inner ends of the pleats are arranged tangentially relative to the center bushing, instead of radially. The invention will be readily understood by reference to the accompanying drawings illustrating one embodiment which the inventive idea may assume, and wherein,

Fig. 1 is a schematic plan view illustrating the shape of a strip of material that is employed in forming the diaphragm of the present invention;

Fig. 2 is a plan view illustrating the strip of material shown in Fig. 1 folded in accordance with the present invention; and

Fig. 3 is a plan view on a larger scale illustrating a diaphragm embodying the present invention.

Referring to the drawings wherein like reference characters refer to like parts throughout the several views, 1 is a strip of any suitable material, for example, paper, of the required width and length as determined by the size of the finished diaphragm. Taking for example a diaphragm of circular shape, this strip is given the form of a rhomboid, the angle between the ends of the strip and the sides thereof being determined by the amount of offset from the radial position which it is desired that the pleats or folds shall have in the finished diaphragm. The strip of material is then pleated, or reversely flexed, the pleats running parallel to the ends of the strip throughout the entire surface of the same. When the pleats are formed in the strips, each pleat is laterally offset with respect to its adjacent pleats. The opposite ends 2, 3 of the pleated strip are then brought

into overlapping engagement and are joined in any suitable manner, as by means of gluing, the fold where the seam occurs being preferably of the same width as the remaining folds.

5 The cylinder now formed is flattened out into a disk in any suitable way. This is preferably done by standing the cylinder on one edge, gathering the opposite ends of the 10 pleats to form a cone, and pushing the apex of the cone downwardly into the plane of the opposite ends of the pleats, thus forcing the latter to open out. Preferably a cylindrical center bushing 4, which may be formed in 15 any desired manner, is inserted in the apex of the cone before the latter is forced downwardly into the plane of the opposite ends of the pleats. The outer periphery of the bushing 4 is preferably covered with a suitable adhesive in order that the inner ends of the pleats may be firmly secured thereto. The usual supporting ring or frame 5 is then 20 attached to the outer ends of the pleats in any suitable or desired manner.

25 It will be found that the inner ends of the pleats do not abut radially upon the bushing 4 but the lines of the folds lie in planes which are substantially tangent to the outer periphery of said bushing. Said inner ends are secured to the periphery of said bushing and 30 are curved to conform with the surface of said bushing, the extent of engagement of said inner ends with said bushing being determined by the angle of the ends of the original rhomboid blank to the long sides thereof.

35 If a diaphragm thus constructed is subjected to changes in atmospheric conditions whereby the pleats tend to increase or decrease in length, the thrust or pull arising 40 from the change in length of the pleats is exerted tangentially on the center bushing 4 so that a slight rotation of said center bushing takes place, the outer ends of the pleats being immovably held by the rigid ring 5 45 which acts as an abutment. An increase in the length of the pleats produces a rotation of the center bushing in one direction, while a decrease in their length produces a rotation in the opposite direction. By this means 50 any variation in the length of the pleats is automatically compensated and the diaphragm remains under tension.

55 It will thus be seen that there is provided a diaphragm which is so constructed as to automatically compensate for changes which tend to vary the volume or to affect the quality of sound produced thereby. Said diaphragm is inexpensive to manufacture and is capable of producing superior results, and is particularly adapted for use where it is desired to employ a diaphragm of large diameter. 60 While the invention has been described and illustrated as applied to a diaphragm of circular shape, it is to be expressly understood 65 that the invention is not limited to dia-

phragms of that form, as by suitably shaping the original blank the resulting diaphragm may be made of any suitable peripheral configuration. Changes may also be made in the construction of the center bushing and surrounding frame without departing from this invention. Reference is therefore to be had to the appended claims for a definition of the limits of the invention.

What is claimed is:

1. A pleated diaphragm having the pleats thereof disposed tangentially to the center of the same. 75
2. A diaphragm formed of a strip of material having the outline of a rhomboid, said strip being pleated and flexed into a disk, the pleats running parallel to the short sides of said strip before it is flexed. 80
3. A diaphragm comprising a strip of pleated material flexed into a disk, and a center bushing, the inner ends of the pleats having tangential engagement with said bushing. 85
4. A device of the class described comprising, in combination with a rigid frame member, a pleated diaphragm secured at its outer periphery to said member, and a center bushing secured to the inner edge of said diaphragm, the pleats of said diaphragm extending tangentially from the outer surface of said bushing. 90
5. A device of the class described comprising a rigid frame member, a center cylindrical member, and a pleated diaphragm secured to said members, said pleats having such engagement with the periphery of said center member that expansion and contraction of the diaphragm tends to rotate said center member. 95
6. A pleated diaphragm having a cylindrical center member with the pleats thereof disposed tangentially to said member. 100
7. A pleated diaphragm formed of a rhomboidal strip of material having folds extending parallel to the short sides of said strip. 105
8. A diaphragm formed of a strip of material having its ends at an oblique angle to the length of said strip, said strip being folded along lines running parallel to the short sides of said strip and flexed into a disk. 110
9. A diaphragm composed of a plurality of elements constituted by pleats, the inner ends of said elements being tangentially arranged relative to the center of the diaphragm, and the outer edge of each element being substantially in a plane normal to the axis of said diaphragm. 115
10. A diaphragm having a plurality of elements constituted by pleats, the inner ends of said elements being tangentially arranged relative to the center of the diaphragm, and means to hold said elements in a flexed position, with the outer ends of said flexed elements in a single plane. 120
11. A device of the class described comprising a center member having a curved outer 125

surface, and a pleated diaphragm, the inner ends of said pleats being attached to said member and being curved to conform with the surface of said member.

5 12. A pleated diaphragm formed of a strip of material, said strip being folded along lines at an oblique angle to its edges.

In testimony whereof I have signed this specification.
